Attorney

UNITED STATES PATENT OFFICE.

ODIN B. WALTERS, OF COUNCIL BLUFFS, IOWA, ASSIGNOR TO LINCOLN ROAD MACHINE CO., OF OMAHA, NEBRASKA, A CORPORATION OF DELAWARE.

DRAFT MECHANISM.

Application filed July 27, 1923. Serial No. 654,290.

To all whom it may concern:

Be it known that I, ODIN B. WALTERS, a citizen of the United States, residing at Council Bluffs, in the county of Pottawattamie and State of Iowa, have invented certain new and useful Improvements in Draft Mechanism, of which the following is a specification.

The present invention relates to draft mechanism and has for an object to provide an improved mechanism of the type for use between wagons, road or other machines, and a draft animal or a tractor, dependent upon the conditions of use.

Another object of the invention is to provide a draft mechanism of this character with means for supporting the weight of the mechanism on the vehicle in such manner that the weight is taken up at all times and the draft mechanism is free to be swung from side to side during the turning of the vehicle or the front wheels thereof.

The invention further provides a draft mechanism which provides a direct coupling between the source of draft and the frame or body of the vehicle or machine being drawn and which also provides an independent connection between the guide wheels of the vehicle or machine and the source of draft so as to cause the vehicle or machine being drawn to follow in the path of the means of draft.

The invention still further provides a substantially semicircular trackway for the forward end of a vehicle or machine and a draft mechanism pivoted to the frame of the machine and having an antifriction device adapted to traverse the trackway and take up the weight of the draft mechanism.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a fragmentary vertical section taken through the forward end of a vehicle

having a draft mechanism constructed according to the present invention applied thereto, the draft mechanism being adjusted for connection with draft animals.

Figure 2 is a top plan view of the same. Figure 3 is a fragmentary vertical section through the forward end of the vehicle showing the draft mechanism adjusted for use with a tractor.

Referring to the drawings which show the draft mechanism of this invention applied to a vehicle of conventional form, 10 designates the side bars of the vehicle frame which are provided with a cross brace 11 near their forward ends and which may have a pair of vertically spaced apart center bars 12. The bars 12 engage across the upper and lower sides of the cross brace 11 and may be secured thereto by a bolt 13 passing through the bars and the brace.

The frame 10 is provided at its under side and at its forward end with a bracket 14 which is arched downwardly from the forward ends of the side bars 10 and which has an arm 15 extending rearwardly and secured upon the bolt 13 to reinforce the bracket 14. Pivoted to the lower end of the bracket 14 is an upwardly arched axle support 16 secured at its ends to the axle 17 upon which the forward wheels 18 of the vehicle or machine are mounted. The axle support 16 is secured by a bolt 19 to the bracket which serves as the pivot for the axle 17.

The axle 17 is attached to the ends of the axle support 16 by straps 20 which engage across the upper face of the spring 16 and receive the clamping bolts 21 therethrough for binding the axle to the axle support spring. The forward ends of the straps 20 are rolled over or otherwise suitably provided with eyes 22 to receive the opposite ends of hinge rod 23, the rod 23 extending across the forward side of the axle 17 and pivotally supporting a web or guide plate 24.

The plate 24 is of any suitable construction but preferably tapers forwardly from the axle and is provided with a flat tongue seat on its upper side to receive the inner end of a vehicle tongue 25 which is detach-

ably clamped to the plate 24 by bolts 26 or the like. This arrangement is shown in Figures 1 and 2. The tongue 25 may thus be utilized for swinging the axle 17 to turn the vehicle or machine 10 and also for holding the axle 17 in its straight line position. The forward end of the plate 24 is provided with a downwardly inclined lip 27 having an aperture 28 therethrough for a purpose which will hereinafter appear.

The forward ends of the center bars 12 of the frame project beyond the cross brace 11 and receive therebetween a draft bar 29 which is pivotally connected between the bars 12 by a bolt 30, the bolts passing vertically through the center and draft bars. The draft bar 29 extends forwardly beyond the machine and is provided with an upwardly spaced or off set strap 31 at its outer end providing a recess or clevis at the forward end of the draft bar to which may be attached the forward draft mechanism. The strap 31 is provided with a bolt 32 which extends downwardly through the strap and through the forward end of the draft bar 29. This bolt 32 is of sufficient length to also pass at its lower end downwardly through the aperture 28 in the lip 27 of the guide plate 24 so that when the tongue 25 is removed from the draft plate, as shown in Figure 3, the draft plate may be attached to the draft bar 29 and swung therewith when the wagon or other vehicle is turned.

For the purpose of supporting the draft bar 29 in its horizontal position, a substantially circular track 33 is mounted upon the forward end of the frame 10 and extends horizontally forward therefrom and curves from one side to the other. The draft bar 29 carries an upwardly extending stud 34 located immediately forwardly of the track 33 and which is bent to overhang the track and provided with a roller 35 adapted to traverse the track and support the draft bar therefrom. It is thus seen that when the draft bar 29 is swung about its pivot 30 the draft bar and parts connected thereto are supported by the stud 34 and roller 35 from the track 33. The draft bar and its parts have thus free and unobstructed swinging movement to turn the vehicle on a short radius in either direction and the draft mechanism is at all times supported from the frame.

As shown in Figures 1 and 2, the draft mechanism may be adjusted for use with draft animals, and in such case a cross bar 36 is positioned between the strap 31 and the draft bar 29 pivoted therebetween upon the bolt 32. The bar 36 carries links 37 at its upper ends to which are connected double trees 38 carrying single trees 39. Of course any other suitable draft means may be used for coupling one or more draft animals to

the draft bar 29. In the instance shown the tongue 25 which is secured to the plate 24 projects forwardly between the draft animals and may be coupled thereto in the ordinary manner for guiding the vehicle to follow the general path of the draft animals.

As shown in Figure 3, when it is desired to use the draft mechanism in connection with a tractor or the like, the tongue 25 is removed from the guide plate 24 and the latter is secured by the bolt 32 beneath the forward end of the draft bar 29. In this instance a coupling bar 40 is placed upon the bolt 32 between the strap 31 and the draft bar 29. The coupling bar 40 may be of any suitable length and character for attachment to a tractor or the like. When the tractor turns in either direction the draft bar 29 is swung therewith upon its pivot 30 and the guide plate 24 is swung therewith so as to turn the axle 17 and change the direction of travel of the vehicle or machine.

While there has been shown and described a particular construction of vehicle or machine, it is understood that the draft mechanism of this invention may be applied to all devices, or machines, wagons or other devices or objects which are to be drawn either by draft animals or by tractors or other power contained vehicles or other source of draft.

I do not wish to be restricted to the size, form, and proportions of the various parts, and obviously changes could be made in the construction herein described without departing from the spirit of the invention, it being only necessary that such changes fall within the scope of the appended claims.

What is claimed is:

1. A draft mechanism for vehicles and the like comprising a draft bar adapted for pivotally mounting upon the frame of a vehicle, means for connecting a source of draft to the forward end of the draft bar, means for supporting the draft bar in a substantially horizontal position from the frame of the vehicle, a pivoted axle mounted beneath the forward end of the vehicle frame, a guide plate mounted on the axle and projecting forwardly therefrom, said guide plate having a tongue seat for receiving the inner end of a tongue thereon to guide the axle by draft animals and said plate having a connecting portion adapted to engage said means for coupling a source of draft to the draft bar for swinging the guide plate with the draft bar to guide the vehicle from a tractor.

2. A draft mechanism for vehicles and the like comprising a draft bar, means for pivotally connecting the draft bar to the frame of the vehicle, means for horizontally supporting the bar in all adjusted positions thereof from the frame of the vehicle, a coupling bolt carried upon the forward end

of the draft bar for connecting animal and tractor draft means to the draft bar, a guide plate pivoted upon the forward axle of the vehicle and having means for attachment to

5 a vehicle tongue for swinging the plate by draft animals to guide the vehicle, said guide plate also having a connecting device

for engagement with said coupling bolt upon the removal of said tongue for guiding the vehicle by the swinging of the draft bar 10 in either direction.

In testimony whereof, I have affixed my signature.

ODIN B. WALTERS.
